UNITED STATES PATENT OFFICE.

ELWOOD WASHINGTON, OF HAMMOND, INDIANA.

AEROPLANE-PLANE.

1,288,318.

Specification of Letters Patent. Patented Dec. 17, 1918.

Application filed June 19, 1918. Serial No. 240,783.

To all whom it may concern:

Be it known that I, ELWOOD WASHINGTON, a citizen of the United States, residing at Hammond, in the county of Lake and State 5 of Indiana, have invented certain new and useful Improvements in Aeroplane-Planes, of which the following is a specification.

This invention relates to aeroplane planes, and more particularly to an upper main 10 plane for an aeroplane.

One of the main objects of the invention is to provide a plane of light but durable construction which may be used in connection with an aeroplane of standard construction. A further object is to provide a plane comprising a collapsible bag or container which may be filled with hydrogen or other suitable gas so as to materially increase the buoyancy of the aeroplane as a 20 whole. Further objects will appear from the detailed description.

In the drawings:

Figure 1 is a top plan view of a plane constructed in accordance with my invention.

Fig. 2 is a section taken substantially on line 2—2 of Fig. 1.

Fig. 3 is a section taken on line 3—3 of Fig. 1.

Fig. 4 is a fragmentary detail view.

In constructing the plane I provide an outer rigid frame 1 of substantially V-shape in cross section, the upper and under faces of this frame being beveled and the apex 35 of the V directed outwardly so as to present a relatively sharp edge thus reducing the resistance of the frame to passage through the air to a minimum. This frame is adapted to be secured to the body and the lower 40 plane of the aeroplane in connection with which it is used by means of suitable braces 2, or in any suitable manner. Frame 1 carries a collapsible gas bag 3 secured there- 45 in and extending completely across the in- terior cross area of the frame so as to close the same. It will be noted that the frame is of substantially rectangular formation and each leg of the frame is substantially V-shaped in cross section so that the mar- 50 ginal edges of the gas bag are forced into the space of V-shaped formation when the bag is inflated. This gas bag may be con- 55 structed of rubberized silk or any other suitable light but strong material and is se- cured in the frame 1 at the edge portion

thereof. By filling the air bag 3 with hydrogen, or other suitable gas, this bag is caused to expand so as to materially increase the buoyancy of the plane. Also, when the bag 3 is filled with gas the under face thereof 60 is stretched relatively tight so as to present a smooth surface to the air in the same manner as a plane of standard construction.

The bag 3 is provided with a suitable valve 4 secured therein by means of which the bag 65 may be filled with gas, or deflated, as required.

The plane constructed in this manner is intended to be used as the top plane for an aeroplane of the multiple plane type. By 70 inflating the bag 3, the buoyancy of this top plane is materially increased, this plane increasing the buoyancy of the aeroplane as a whole so as to permit it to be driven at relatively slow speed, when desired, for 75 purposes of observation, bombing, and other purposes. Also due to this increase of buoyancy, an aeroplane equipped with an inflatable upper plane of this type is capable of alighting easily thus eliminating the danger of accident which occurs in aeroplanes 80 of ordinary type the planes of which are not inflatable. If desired, the frame 1 may be provided with a plurality of transversely reinforcing and retaining members positioned above the bag 3 so as to effectually 85 eliminate all possibility of the bag being pulled out of the frame 1, though I do not consider these members necessary under ordinary conditions.

The foregoing description and the drawings have reference to what may be considered the preferred or approved form of invention. It is to be understood, however, that I may make such changes in construction and arrangement and combination of parts, materials, dimensions, etc., as may prove expedient and fall within the scope 95 of the appended claims.

Having thus described my invention, what 100 I claim as new and desire to secure by Letters Patent is:

1. In a plane for aeroplanes, a retaining frame of substantially rectangular formation, each leg of the frame being substantially V-shaped in cross section whereby a V-shaped space is provided extending completely around the frame, an inflatable gas bag received in the frame and adapted to have its marginal edges extended into the 110

V-shaped frame whereby the said bag will be maintained in position in the frame when the bag is inflated.

2. In a plane for aeroplanes, a retaining frame of substantially V-shape in cross section, the upper and under faces of said frame being oppositely inclined so as to provide a relatively sharp edge for reducing resistance of passage through the air of the plane, and an inflatable gas bag secured in said

frame and extending over the full interior area thereof, said gas bag being adapted to receive a gas for increasing the buoyancy thereof.

In testimony whereof I affix my signature 15 in presence of two witnesses.

ELWOOD WASHINGTON.
